CHEWING GUM PACKAGE

Tom Huston, Hartford, Conn., assignor to Shelby
P. Langston, Miami, Fla.

Application October 20, 1936, Serial No. 106,592

3 Claims. (Cl. 206—46)

My invention relates to chewing gum packages.

It has among its objects to provide an improved gum package and more particularly an improved package of an improved folded type adapted to be folded in an attractive and convenient form when the gum is shipped, offered for sale, or carried in the pocket, and to be opened after the manner of a wallet to permit a gum stick to be very conveniently removed.

10. A further object of my invention is to provide such an improved package having an improved double ended non-collapsible compartment structure adapted to retain its shape during shipment or display, or while carried in the pocket, and 15 further, adapted to provide an improved attractive and convenient arrangement of the gum sticks in a plurality of series of parallel sticks extending longitudinally of the package and in such manner as to be very conveniently accessible 20 when the package is opened.

A still further object of my invention is to provide such an improved package having such improved compartments and an improved non-collapsible transverse flexible connection there- 25 between so that the package may be readily opened after the manner of a wallet, with the package flexed backward to dispose the gum sticks on opposite sides of said transverse flexible portion at such an angle to one another as to 30 permit ready removal of any selected stick by grasping the end of the stick adjacent the flexible portion of the package.

Still further objects of my invention are to provide such an improved gum package which is 35 also adapted to retain the gum sticks securely therein and one which will further maintain its shape despite handling or the removal of one or more of the gum sticks therefrom. Still another object of my invention is to produce such an im- 40 proved gum package which while having the advantages above set forth, is also adapted to be very inexpensively produced.

These and other objects and advantages of my improved construction will however hereinafter 45 more fully appear.

In the accompanying drawing, I have shown for purposes of illustration one embodiment which my invention may assume in practice.

In the drawing—

50. Figure 1 is a perspective view of this form of my improved wallet type package as held open in the hand during the process of removing a gum stick therefrom;

Fig. 2 is a perspective view showing the package 55 in closed position;

Fig. 3 is a side elevation of the closed package shown in Figure 2;

Fig. 4 is a similar side elevation with the package laid out flat to show features of its construction, and

Fig. 5 is a perspective view of the package when disposed flat as shown in Figure 4, to bring out other features of this construction.

Referring to Figures 1 to 5, it will be noted that I there show my improved package as formed from a single body or blank, generally indicated at B. This blank is preferably of rather thin cardboard and carries on opposite sides of a transverse flexible portion a plurality of longitudinally spaced series of gum sticks, indicated in 10 at G, the sticks in each series being arranged in parallel relation in the same plane and lengthwise of the package. As shown, my improved package is also provided at its opposite ends with 15 improved non-collapsible gum stick retaining compartment means, and with an improved transverse flexible connection between the series of gum sticks; all whereby it is made possible to produce my improved wallet type package 20 openable into the position shown in Figure 1 and also adapted to be folded or closed to the position shown in Figure 2 during shipment or when on 25 display or when carried in the pocket.

Referring more particularly to my improved 30 construction, it will be noted that the blank B is transversely scored on parallel lines at 1 and 2, adjacent the remote ends of the two series of gum sticks, the distance between the scorings 1 and 2 being substantially equal to the thickness of the 35 sticks. Further, it will be noted that I provide compartment forming portions 3 which extend from the scorings 2 over the adjacent ends of the gum sticks, these portions 3 herein being provided with clipped corners. Thus, the two 40 portions 3 extend in opposite directions toward one another and form slots closed at their outer ends and opening toward the center in which the remote extremities of the series of gum sticks are 45 enclosed while the opposite ends of the sticks are so exposed as to be readily accessible. Further, it will be noted that herein the gum sticks G are 50 also disposed in suitable tubular compartments or sheath members 4 suitably attached by adhesive as at 5 to the upper face of oppositely extending gum carrying portions 6 of the blank B, each of 55 these portions 6 being of substantially the length and width of the series of gum sticks when the latter are laid close together as shown. Thus, the portions 3 connected to portions 6 by vertical 60 end walls 7 between the parallel scoring lines 1

and 2, and also the tubular sheath members 4, provide compartment means in which the several gum sticks are disposed and cooperate in effectively retaining the sticks against loss or dis-
5 placement. Further, it will be noted that due to the scoring lines 1, 2, the end portions 7 and portions 3, a substantially non-collapsible compartment structure is provided and one in which the two members 3 may lie flat in engagement
10 with one another in the closed position of the package without causing gapping or an angular disposition of either member 3.

Intermediate the two series of gum sticks, I also provide transverse parallel scoring lines 8 and 9 disposed on opposite sides and equally spaced from the transverse center line. As shown, these lines 8 and 9 are adjacent the adjacent ends of the different series of sticks and are spaced by an intermediate portion 10 of the
15 body B which is of substantially the width of the combined thickness of the two series of gum sticks. Thus, it is not only made possible for the two gum carrying portions 6 to be folded from the position shown in Figures 4 and 5 to the position shown in Figure 2 wherein the two end members abut in substantial parallelism, but also, by reason of the portion 10 and the two portions 7, to produce the substantially non-collapsible double ended flat lying package shown in Figure
20 2 and having means at each end which resist collapse. Moreover, it will be noted that due to the provision of the intermediate flexible portion comprising the portion 10 connected by the scoring lines 8 and 9 to the gum carrying portions 6, it is also made possible for the package shown closed in Figures 2 and 3, to be opened after the manner of a wallet and disposed in the position shown in Figure 1 whenever it is desired to remove a stick. More particularly, the construction is such that with the outer face of one portion 6 resting upon the fingers of, for example, the left hand, as shown in that figure, the other portion is enabled to drop downward into the angular relation shown relative to the portion 6 held in the hand, in such manner as thus to expose the adjacent ends of both series of gum sticks G so that any selected one of the same may be very conveniently withdrawn from its sheath 4, as by the thumb and fingers of the
30 right hand. Also of course it will be evident that when the package is so disposed, if the user wishes to tear off any selected stick and wrapper as a unit, rather than pull the stick out of its wrapper, this also may be very conveniently done.
35 55 As a result of my improved construction, it is made possible to produce an improved and attractive flat package wherein the gum is very compactly packed and wherein gapping is eliminated. Further, the construction is such that the package retains its shape and continues to perform its function even after the removal of one or more sticks of gum, as distinguished from permitting the gum sticks to be separated as in the usual gum package. Moreover, the package
60 65 is very convenient in that it is readily opened and disposes the adjacent ends of all of the sticks so that they may be readily removed by withdrawing the foil or paper wrapped sticks from the sheaths while leaving the latter attached to the package. Further, it will be noted that due to the improved non-collapsible structure at the opposite ends of the folded package, a form of pack-
70 75 age is provided which is well adapted to stand handling, while my improved compartment forming means also effectually prevent the loss of

sticks from the package. Attention is also di-
rected to the fact that since my improved pack-
age may be made from a single sheet of material,
it may be very inexpensively produced, while the
structure is also such as readily to lend itself
5 to manufacturing and filling by automatic ma-
chinery. Attention is also directed to the fact
that the structure is such as to produce panels
of substantial size on each face of the package
when closed, in such manner as to provide at-
tractive advertising space, while of course the
ability of the package to stand up under long
continued carrying in the pocket also increases
the advertising value of the matter carried on
the package. These and other advantages of my
10 15 improved construction will, however, be clearly
apparent to those skilled in the art.

While I have in this application specifically
described one form which my invention may as-
sume in practice, it will be understood that this
form is chosen for purposes of illustration, and
that the invention may be modified and embodied
in other forms without departing from the spirit
or the scope of the appended claims.

What I claim as new and desire to secure by
Letters Patent is:

1. A package for holding a plurality of articles
to be selectively dispensed, including two article
carrying portions foldable into closed position
and having a transverse flexible portion there-
between, tubular article holding means secured
in parallel relation to said article carrying por-
tions with their adjacent open ends toward and
adjacent said flexible portion and closed thereby
when said package is closed, said article holding
means being disposable between said article car-
rying portions when the latter are closed, said
article carrying portions having flexible exten-
sions at their ends remote from said foldable
portion forming end closures for said article hold-
ing means at the open ends thereof remote from
said flexible portion and also forming flaps over-
lying portions of said article holding means adja-
cent said last mentioned ends.

2. A package for holding a plurality of articles
to be selectively dispensed including two article
carrying portions foldable into closed position
and having a flexible portion therebetween, a plu-
rality of tubular individual article holding sheath
members attached to each of said article carry-
ing portions longitudinally thereof with their
adjacent open ends toward said foldable portion
and closed by the latter when the package is
closed, and flap means on the free ends of said
article carrying portions for closing the other
open ends of said sheath members and having
55 their extremities overlying each other and the
adjacent portions of said sheath members and
disposed between the latter members when the
package is closed.

3. A gum package comprising a longitudinally
extending member having longitudinally spaced
carrying portions each having secured thereto
a plurality of tubular gum stick receiving sheath
members secured in parallel relation longitudi-
nally thereof and having a transverse flexible
portion therebetween transversely scored on par-
allel lines spaced longitudinally by a distance
substantially equal to the thickness of two sheath
members to permit closing of said package by
70 folding said article carrying portions into overly-
ing parallel relation wherein said flexible portion
forms a closure for the adjacent open ends of
said sheath members, said carrying portions also
being transversely scored at their remote ends on
75

parallel lines spaced by a distance substantially equal to the thickness of a single sheath member to form right angle closure portions for the remote ends of said sheath members and having
5 end flap members beyond said second scoring adapted to overlie the remote end portions of said

sheath members while exposing the portions thereof adjacent said flexible portion and engageable in substantially parallel relation when said package is closed.

TOM HUSTON. 5
